UNITED STATES PATENT OFFICE.

LOUIS B. LONDON, OF NEW YORK, N. Y.

DESIGN FOR AN INVERTED GAS ARC-LAMP.

41,772.

Specification for Design.

Patented Sept. 12, 1911.

Application filed February 21, 1910. Serial No. 545,260. Term of patent 3½ years.

To all whom it may concern:

Be it known that I, LOUIS B. LONDON, a citizen of the United States, residing in the borough of Brooklyn, city of New York, in the county of Kings and State of New York, have invented a new, original, and ornamental Design for Inverted Gas Arc-Lamps, of which the following is a specification, reference being had to the accompanying drawing, forming part thereof.

The figure is a view in elevation of an inverted gas arc lamp showing my new design.

I claim:

The ornamental design for an inverted gas arc lamp as shown.

L. B. LONDON.
